UNITED STATES PATENT OFFICE

2,146,376

SCALP PROTECTOR

Morris Lyons, Chicago, Ill.

Application May 3, 1937, Serial No. 140,286

7 Claims. (Cl. 132—33)

This invention relates to a device for the permanent waving of hair, and more particularly to a scalp protector and spacer.

This application is for an improvement of my invention for scalp protectors filed May 22, 1935, Serial Number 22,752, which relates to spiral windings, the present invention relating to croquinole windings.

One of the objects of my invention is to provide a simple, practical, and convenient article of the character described. Another object is to provide a scalp protector that is economical to construct and efficient to manipulate. Another object is to provide a device for securing a permanent waving element to a lock of hair and at the same time to protect the scalp from injury by accidental exposure to heat, steam, or other hot liquid. A further object is to combine in a single device a scalp shield and a permanent waving device.

Other objects and advantages will appear and be brought out more fully in the following specification, reference being had to the accompanying drawing, in which:

25 Fig. 1 is a top view in closed position of a device embodying the principles of my invention.

Fig. 2 is a similar view of the same in open position.

Fig. 3 is a longitudinal section taken along the line 3—3 of Fig. 1.

Fig. 4 is a similar longitudinal section taken along the line 4-4 of Fig. 1.

Fig. 5 is a cross section taken along the line 5-5 of Fig. 1.

35. Fig. 6 is a similar cross-section taken along the line 6—6 of Fig. 1.

Fig. 7 is a separate view of the spindle element. Fig. 8 is a perspective view of one of the pads and rod assembly.

40 Fig. 9 is a similar view of a complementary pad and pad retainer elements.

Fig. 10 is a side view of the device, illustrating the same in use, and

Fig. 11 is an enlarged view in section of the same taken along the line 11-11 of Fig. 10.

Referring more particularly to the drawing, it shows a scalp protector and spacer generally.

show a scale protector and spacer generally by the number 15, which comprises a relatively fixed member 16, a relatively movable or pivoted mem-

50 member 17, a lock member 18, and a spindle or curling rod 19. Member 16 consists essentially of an elongated channel 20, having an upper plate 21 provided with an edge 21a, a side wall 22, a lower wall 23, and flange 24. Upper plate 21 is formed 55 with an extension 25 at one end thereof, which is

turned up forming an end wall 26, the latter being provided with a slot 27. End walls 28 are formed in lower wall 23 and one of the end walls 28 is provided with an ear 29, and the other end wall is provided with an ear 30. Ear 29 is formed with an offset extension 29a for a purpose to be hereinafter more fully explained. A lock rivet 31 secures together extension 25 and ear 29. A felt pad 32 is located in the lower portion of channel 20, and a similar pad 33 fills the remainder of the channel and has an exposed side abutment edge portion 33a.

In Fig. 8 I show a pad and pad retainer comprising a pad retainer 34, preferably formed of flexible rubber in the form shown, having a top wall 35, side wall 36, base 37, side wall 38, and a top wall 39, which, as will be clear from Fig. 11, is adapted to be clamped to channel 20, the top wall 39 overlapping a portion of pad 32. A scalp pad 40 of felt or equivalent material is suitably secured to pad retainer 34 and has a contact edge 40a.

Member 17 is constructed substantially similar to member 16 and consists of a channel 41, having an upper plate 42, side wall 43, lower plate 44, and flange plate 45, the upper plate 42, having a flange abutment 42a, which is adapted to overlap the top wall 39 of pad retainer 34, and substantially contact abutment edge 33a of pad 33 when the device is in closed position. Plate 44 has an end wall 46 and an ear 47. A pivot bolt 48 is secured between flange extension 25 and offset extension 29a, and extends through end wall 46 and ear 47, by which the member 17 is adapted to pivot with respect to member 16. A washer 49 is located between offset extension 29a and the head of pivot bolt 48. Upper plate 42 is formed with an offset 50 and lower plate 44 is formed with a similar offset 51 which together form a latch catch 52 for cooperation with a latch to be presently more fully explained. A pad retainer 53 for member 17 is provided with a top wall 54, side wall 55, base 56, a side or abutment wall 57, and a top wall 58. The ends of pad retainer 53 are retained against longitudinal displacement by end wall 46 of plate 44 and offsets 50 and 51 of upper plate 42, and lower plate 44, respectively. A scalp pad 59 similar to pad 40 is secured to pad retainer 53 and has an abutment or contact edge 59a adapted to register with contact edge 40a of pad 40. A guide arm 60 extends outwardly from flange 24 and serves to prevent upward movement of member 17 with respect to member 16 when in use. An angle plate 61 is secured to a strap 62 by pivot pins 63.

63 and 64, pin 63 extending through the ear 30 on upper plate 20, washer 65 being employed for the heads of pins 63 and 64. A wall 66 extends at right angles from plate 61 and has a slot 67, the side walls of which are parallel. An eccentric latch 68 is secured between plate 61 and strap 62 and is adapted to pivot on pivot pin 64, and has the usual operating arm 69 by which the latch may be engaged with catch 52 when the device is in closed position, as shown in Fig. 1. Extension 25 is provided with an abutment 25a and ear 30 with an abutment 30a, by which accidental longitudinal displacement of pad retainer 34 is prevented. Similarly, abutments 47a and 52a are formed in plate 42 to prevent such similar movement of pad retainer 53 on member 17. The spindle or curling rod 19 is shown in Fig. 7 as having a handle 70 and an internally secured bearing stud 71 on which the spindle 19 is rotatable and locked when the square head 72 of the bearing stud is positioned in slot 67, the width of which is that of the side dimension of head 72. The spindle is shown as having the usual hair clamp 73.

26. In Figs. 10 and 11 the device is shown in use, wherein a portion of the scalp is indicated at A, and a lock of hair B wound on the spindle 19 and clamped between the pads 40 and 59 and between the walls 38 and 57 of the pad securing members. It will be clear that flange abutment 42a securely holds the lock of hair in a double bend against the abutment edge 33a of pad 33. From the foregoing description, it will be clear that the lock of hair is tightly and securely held 35 in the device against the scalp, which will be protected by the pads and rubber retaining elements and that there will be no possibility of the scalp becoming exposed to heat in either liquid or fluid form, in view of the effectively aligned and 40 securely held abutment edges, as well as the overlapping of flange 42a.

While I have illustrated and described the preferred form of construction selected for illustrating the principles of my invention, and for carrying the same into effect, the same is capable of variation and modifications without departing from the spirit of the invention. I therefore do not wish to be limited to the construction set forth, but desire to avail myself of such variations and modifications as come within the scope of the appended claims.

I claim:

1. In a device of the class described, a pair of clamping members, a hinge connecting the members at one end, locking means at the opposite ends of said members, resilient removable pad retainers on each of said clamping members, said retainers having walls fitting against the bottoms and the inner and outer faces of said clamping members and flanges extending over the upper edges thereof, and pads fixed to the lower walls of said retainers and having the ends thereof projecting beyond said retainers and under said hinge and said locking means, substantially as described.

2. In a device of the class described, a pair of clamping members, each formed of sheet metal and comprising a bottom wall, vertical inner and outer side walls and inturned flanges at the upper edges of said outer side walls, the said flange of one of said clamping members projecting entirely over the same and to adjacent the edge of the flange on the opposite member and pads covering the bottom walls and the inner and outer

side walls of said clamping members, substantially as described.

3. In a device of the class described, a pair of clamping members, each formed of sheet metal and comprising a bottom wall, vertical inner and outer side walls and inturned flanges at the upper edges of said outer side walls, the said flange of one of said clamping members projecting entirely over the same and to adjacent the edge of the flange on the opposite member, a pad enclosed within the last said member and adapted for cooperative clamping action with the over-projecting flange on the other clamping member, and pads covering the bottom walls and the inner and outer side walls of said clamping members, substantially as described.

4. In a device of the class described a relatively fixed and a relatively movable clamping member, each formed of sheet metal and comprising a bottom wall, vertical inner and outer side walls and inturned flanges at the upper edges of the outer side walls, the inner walls terminating in planes below that of said flanges and the inturned flanges on the relatively movable member extending entirely over said member and to adjacent the edges of the flange on the relatively fixed member, and resilient removable pad retainers on each of said clamping members, each of said retainers having walls fitting against the bottom and side walls of said clamping members respectively and provided with flanges extending over the upper edges of the inner side walls of the clamping members and over the outer portions of the top flanges thereof, substantially as described.

5. In a device of the class described relatively fixed and relatively movable clamping members, each formed of sheet metal and comprising a bottom wall, vertical inner and outer side walls and inturned flanges at the upper edges of the outer side walls, said inturned flanges on the relatively movable member extending entirely over said member and to adjacent the edge of the flange on the relatively fixed member, the inner walls terminating in planes below that of the said flanges, and that of the relatively fixed member terminating in a plane below that of the upper edge of the adjacent wall of the relatively movable member whereby space is provided for the hair below said over-extending flange, and resilient removable pad retainers on each of said clamping members, each of said retainers having walls fitting against the bottom and side walls of said clamping members respectively and provided with flanges extending over the upper edges of the inner side walls of the clamping members and over the outer portion of the top flanges thereof, substantially as described.

6. In a device of the class described relatively fixed and relatively movable clamping members, each formed of sheet metal and comprising a bottom wall, vertical inner and outer side walls and inturned flanges at the upper edges of the outer side walls, said inturned flange on the relatively movable member extending entirely over said member and to adjacent the edge of the flange on the relatively fixed member, the inner walls terminating in planes below that of the said flanges, and that of the relatively fixed member terminating in a plane below that of the upper edge of the adjacent wall of the relatively movable member whereby space is provided for the hair below said over-extending flange, a pad within said relatively fixed member and extending laterally beyond the inturned flange for clamping cooperation

with the edge of said over-extending flange, and resilient removable pad retainers on each of said clamping members, each of said retainers having walls fitting against the bottom and side walls of said clamping members respectively and provided with flanges extending over the upper edges of the inner side walls of the clamping members and over the outer portion of the top flanges thereof, substantially as described.

10 7. In a device of the class described relatively fixed and relatively movable clamping members, each formed of sheet metal and comprising a bottom wall, vertical inner and outer side walls and inturned flanges at the upper edges of the outer side walls, said inturned flange on the relatively movable member extending entirely over said member and to adjacent the edge of the flange on the relatively fixed member, the inner walls ter-

minating in planes below that of the said flanges, and that of the relatively fixed member terminating in a plane below that of the upper edge of the adjacent wall of the relatively movable member whereby space is provided for the hair below 5 said over-extending flange, a removable pad within said relatively fixed member and extending laterally beyond the inturned flange for clamping cooperation with the edge of said over-extending flange and resilient removable pad retainers on 10 each of said clamping members, each of said retainers having walls fitting against the bottom and side walls of said clamping members respectively and provided with flanges extending over the upper edges of the inner side walls of the 15 clamping members and over the outer portion of the top flanges thereof, substantially as described.

MORRIS LYONS.
